UNITED STATES PATENT OFFICE.

ORRIN R. STROME, OF MELFORT, SASKATCHEWAN, CANADA.

ROTARY-BRUSH SWEEPER.

1,383,440.

Specification of Letters Patent.

Patented July 5, 1921.

Application filed May 3, 1919, Serial No. 294,514. Renewed January 8, 1921. Serial No. 435,988.

To all whom it may concern:

Be it known that I, ORRIN R. STROME, a subject of the King of Great Britain, residing at Melfort, in the Province of Saskatchewan, Dominion of Canada, have invented certain new and useful Improvements in Rotary-Brush Sweepers; and I do hereby declare the following to be a full, clear, and exact description of the invention, such as will enable others skilled in the art to which it appertains to make and use the same.

The present invention relates to new and useful improvements in sweeping apparatuses, more particularly of that type including rotary brushes adapted to be propelled over the surface to be cleaned.

It is in general the object of the present invention to simplify and otherwise improve the structure and to increase the efficiency and readiness of operation of brushes of this character, and more particularly of that small type adapted for household use.

A more detailed object resides in the provision of an arrangement for effecting an oblique disposition of the sweeping elements with respect to their direction of movement, wherein the dirt swept is projected in the direction of movement, this arrangement being procured in an exceedingly simple structure wherein the sweeping elements are driven from the center of the device.

With the above and other objects, and advantages in view, the invention resides more particularly in the novel combination, formation and arrangement of parts herein-after described and particularly pointed out in the appended claim.

In the accompanying drawings:

Figure 1 is a plan view of a sweeper constructed in accordance with the present invention.

Fig. 2 is an end elevation thereof.

Fig. 3 is a sectional view on the line 3-3 of Fig. 1.

Fig. 4 is a vertical sectional view taken through the central portion of the device on the line 4-4 of Fig. 1.

Fig. 5 is a fragmentary plan view showing a modified form of roller drive wherein angular adjustment of the rollers is permitted.

Fig. 6 is a horizontal sectional view therethrough.

Fig. 7 is a detail fragmentary section, showing the mounting of the brush supporting arms.

Referring now more particularly to the accompanying drawings, the frame of the device comprises a loop or casting 10 having at the free ends of its legs a pair of bearing sleeves 11 in which is journaled an axle 12 which extends a considerable distance outwardly of the bearing sleeves and has fixed thereon at its ends the driving ground wheels 13. The truck thus formed is propelled by grasping the cross bar grip 14 of a handle 15 to the inner end of which is secured the inwardly offset ends of bars 16 secured to the bearing sleeves 11, the connection of the bars 16 and handle 15 being preferably pivotal whereby to permit free movement of the handle. Secured to the bight portion of the loop or casting 10 is a bar 17, the ends of which extend divergently outwardly from the casting in the form of a pair of arms 17 which carry bearing sleeves 18 at their outer ends and which are braced by bars 19 secured to their outer ends and to the casting 10, it being observed that the axes of the bearing sleeves 18 are oppositely inclined with respect to the axis of the device.

Secured against the bar 17 at the center thereof is a U-shaped yoke 20, the arms of which extend forwardly in the direction of movement of the device and carry bearings 21 in which is journaled a counter shaft 22. Journaled in the bearing sleeves 18 are the inner end portions of brush roller shafts 23, which are connected at their inner ends with the counter shaft 22 by universal couplings 24, and said shafts 23 are thus held at two points to extend divergently forward in the direction of movement of the device. Mounted on the shaft 22 between the legs of the yoke 20 is a pulley 25 and mounted on the axle or drive shaft 12 between the bearing sleeves 11 is a pulley 26 of relatively larger diameter, the peripheries of these pulleys being provided with grooves 100 V-shaped in cross section to snugly receive a belt 27 which has its stretches between the pulleys crossed.

Thus as the structure described is propelled over the ground, the forwardly inclined brush shafts 23 will be rotated in a direction opposite to rotation of the axle or drive shaft 12.

Disposed on the brush shafts 23 are the sleeve hubs 28 of brush rollers 29, and these sleeve hubs are held against relative movement on the shafts by abutment at their

inner ends with a stop shoulder 30 on the shafts, and by abutment at their outer ends with retaining nuts 31 threaded on the shafts. To provide a clearance for the driving and supporting mechanisms of the shafts, and retain an efficient sweeping action at the center of the device, the inner ends of the brush rollers are concave, whereby their peripheral end portions are retained in contact, and the outer ends of the brushes are preferably also dished to permit brushing against a wall or the like without damage thereto by the end of the roller shaft.

15 An exceedingly simple and compact sweeper has thus been provided, attention being particularly directed to the grouping of the entire drive mechanism at the center of the brush structure without interference with a continuous sweeping actuation from one end of the brush structure to the other.

20 In Figs. 5 and 6, a slightly modified structure is shown, which permits angular adjustment of the brushes, to vary the sweeping width of the device, and to vary the amount of sweeping action exerted on a given surface in the travel of the device. In this structure, forwardly extending bracket arms 17^a are adjustably secured to the sides of the casting 10 by bolts 33 passed through slots 24 in the said casting and through the bracket arms and provided with clamping wing nuts 35. Pivoted to the outer 25 ends of the bracket arms are bearing collars 18^a receiving brush roller shafts 23, and the inner brush stops of these shafts are preferably in the form of nuts 30^a threaded on the inner ends of the shafts to adjust the 30 positions of the inner ends of the brush in accordance with the angular adjustment

of the shafts 23 effected by shifting the bracket arm 17^a, whereby said shafts will be swung about their universal couplings 24 as pivots. In this form of the invention, the bar 17' is omitted, the yoke 20 being secured directly against the casting 10.

45 It will be also understood that further modifications and changes of structure may be resorted to, to meet differing conditions 50 of use without departing from the spirit of the invention as claimed.

What is claimed is:

In a sweeper, the combination with a handle having a grip at its front end, bars 55 pivoted to its rear end, a loop having spaced bearings to which said bars are connected, the sides of the loop having longitudinal slots, a main shaft journaled through the bearings and having ground wheels at its 60 ends, and a driving wheel fast on said shaft between such bearings; of a yoke carried by the loop and having bearings in its arms, a counter shaft journaled through these bearings and carrying a driven wheel between them, operative connections between said wheels, brush shafts connected by universal joints with the ends of the counter shaft and carrying roller brushes, bearing collars for these shafts between said brushes 70 and joints, arms pivoted to said collars and leading alongside said yoke, and bolts through such arms and adjustable in said slots for varying the position of the brush shafts with respect to the counter shaft. 75

In testimony whereof I affix my signature, in the presence of two witnesses.

ORRIN R. STROME.
